UNITED STATES PATENT OFFICE.

WILLIAM F. SIGLER, OF LINCOLN, NEBRASKA.

COMBINED OIL-CUP AND PACKING-GLAND.

1,365,556.

Specification of Letters Patent. Patented Jan. 11, 1921.

Application filed April 17, 1920. Serial No. 374,606.

To all whom it may concern:

Be it known that I, WILLIAM F. SIGLER, a citizen of the United States, and a resident of Lincoln, in the county of Lancaster and 5 State of Nebraska, have invented a new and useful Improvement in Combined Oil-Cups and Packing-Glands, of which the following is a full, clear, and exact description.

My invention relates to improvements in 10 combination oil cups and packing glands, and it consists in the combinations, constructions, and arrangements herein described and claimed.

An object of my invention is to provide 15 a novel form of combination oil cup and packing gland, which is designed for use with a mechanism provided with an upright piston rod, and which is provided with means for effectively lubricating the piston 20 rod while also performing the function for which a packing gland is ordinarily employed.

A further object of my invention is to provide a device of the type described in 25 which means is provided for keeping the piston rod constantly immersed in a lubricant.

A further object of my invention is to provide a device of the type described, 30 which can be filled with a lubricating substance while the apparatus to which applied is in service.

A further object of my invention is to provide a device of the type described in 35 which means is provided for preventing the lubricating fluid being ejected by the operation of the piston rod.

A further object of my invention is to provide a device of the type described that 40 is durable in construction and thoroughly practical commercially.

Other objects and advantages will appear in the following specification, and the novel features of the invention will be particularly pointed out in the appended claims.

My invention is illustrated in the accompanying drawings, forming part of this application, in which—

The figure is a side elevation of the device 50 operatively applied, portions being broken away and other portions being shown in section.

Referring to the accompanying drawings, it will be noted that I make use of a pair 55 of vertically disposed co-axially aligned cylinders 1 and 2 provided respectively with

cylinder heads 3 and 4 which are secured thereto in an ordinary manner, as by bolts 5. A piston rod 6 is arranged to be reciprocated within the cylinders 1 and 2. The 60 parts described so far are of ordinary construction and form no part of my invention except in so far as they coöperate with the parts about to be described.

It will be noted that I provide a casing 65 having an enlarged bowl-like upper portion 7 and being formed with a vertically extending central bore 8 which is adapted to receive the piston rod 6. The central bore 8 opens at its upper end into a cavity 9 in 70 which a lubricating substance is placed. The upper edge of the enlarged portion 7 is beveled and is formed with an inwardly extending integral flange 10 which overhangs the cavity 9 and prevents the lubricating substance placed therein being ejected by the operation of the piston rod 6.

A cylindrical lower portion 11 of the casing is formed with a central recess 12 through which the piston rod 6 extends. 80 Packing 14 is arranged between the inner wall of the central recess 12 and the piston rod 6. The lower portion 11 of the casing may be secured to the cylinder head 4 in any suitable manner. In the embodiment of my 85 invention illustrated in the accompanying drawings, I have shown the lower end thereof of reduced and threaded exteriorly at 13. This threaded end 13 is screwed into a threaded opening 15 which is formed 90 through the cylinder head 4. The lower portion 11 of the casing has a plurality of vertically extending grooves 16 in its outer surface which are adapted to receive the jaws of a spanner wrench so that the 95 casing can be conveniently secured in operative position.

From the foregoing description of the various parts of the device, the operation thereof may be readily understood. A lubricating substance is placed within the cavity 9 and will keep the piston rod 6 constantly lubricated, thereby preventing the wearing out of the piston rod as quickly as is the case when my improved device is not 105 used.

The arrangement of the oil cup and packing gland will more than double the life of the packing and should therefore effect a saving of nearly 100% in labor. Since 110 the piston rod is effectively lubricated, the entire apparatus, to which the device is ap-

plied, will function to better advantage. A properly lubricated piston, will to a great extent, assist lubricating the cylinder particularly since the piston is vertically disposed. The inwardly extending beveled flange 10 will prevent the lubricating substance being blown from the cup by the operation of the piston rod. One of the principal advantages of the device lies in the 10 fact that the cup can be refilled while the piston rod is being operated. Furthermore, when it is desired to renew the packing, it is not necessary to remove the device from the piston rod as it will be obvious that the 15 device may be moved along the piston rod 6 until the packing gland 17, which is shown in the accompanying drawings as being secured to the cylinder head 3, is partly received within the cavity 9, thereby affording 20 ample space for performing the work required and permitting access to the cylinder 1.

I claim:

1. The combination with a cylinder having a cylinder head and a vertically disposed piston rod mounted to be reciprocated therein, of a combination oil cup and packing gland comprising a single integral casing formed with a vertically extending central 25 bore adapted to receive the piston rod, said casing having a bowl-like upper portion provided with a substantially bowl-shaped 30

cavity for holding a lubricating substance and having its upper edge beveled and fashioned with an inwardly extending annular 35 flange arranged to overhang the cavity, and a lower cylindrical portion having a vertically extending central recess adapted to receive packing, said lower portion having its lower end reduced and threaded for screwing 40 in a threaded opening in a cylinder head and having a plurality of vertical grooves provided in its outer surface.

2. The combination with a cylinder having a cylinder head and a vertically disposed piston rod mounted to be reciprocated therein, of a combination oil cup and packing gland comprising a casing formed with a vertically extending central bore adapted to receive the piston rod, said casing having a 45 bowl-like upper portion provided with a cavity for holding a lubricating substance and having its upper edge beveled and fashioned with an inwardly extending annular flange, and a lower cylindrical portion having a vertically extending central recess adapted to receive packing, said lower portion having its lower end reduced and threaded for screwing 50 in a threaded opening in a cylinder head and having a plurality of vertical grooves provided in its outer surface.

WILLIAM F. SIGLER.
